VIBRATORY SCREEN

Alex T. Cecil, Columbus, Ohio, assignor to The
Traylor Vibrator Company, a corporation of
Colorado

Application December 28, 1938, Serial No. 248,054

7 Claims. (Cl. 209—382)

This invention relates to a vibratory screen and more particularly to such a screen including tappers which co-operate with the screen cloth to prevent blinding.

An object of the invention therefore is to provide a screen of the above described type having one or more tappers which co-operate with the screen cloth to prevent blinding, particularly when the material being screened is relatively fine material which tends to blind the screen cloth, examples of which are finely ground bauxite, alum, and silicate sand.

Another object of the invention is to provide a simple and efficient tapper for a vibratory screen.

Other objects of the invention will appear hereinafter, the novel features and combinations being set forth in the appended claims.

In the accompanying drawings,

Fig. 1 is a side elevational view of a vibratory screen comprising my invention;

Fig. 2 is a front elevational view of the screen of Fig. 1;

Fig. 3 is a transverse sectional view taken on the line 3—3 of Fig. 1, looking in the direction of the arrows;

Fig. 4 is an enlarged sectional elevational view taken on the line 4—4 of Fig. 3, looking in the direction of the arrows; and

Fig. 5 is a perspective view of a tapper comprising one aspect of my invention.

It has been found in practice that certain materials particularly when in a very finely ground state, examples of which are finely ground bauxite, alum and silicate sand, tend to blind or clog the screen cloth of a vibratory screen. I have provided an improved type of screen and tapper mechanism which in practice has been found very efficient in eliminating this blinding action.

Referring particularly to Figs. 1 and 2 of the drawings there is illustrated a vibratory screen incorporating the features of my invention which in general takes the form of the screen disclosed in more complete detail in the patent to James A. Flint, No. 2,137,753, dated November 22, 1938, for a Vibratory screening device, to which reference is made for a more complete disclosure of the screen, except, however, that the screen of the above-mentioned patent is a double deck reaction type screen, while that of the instant application is a single deck direct action type screen which makes for certain differences which are obvious and which will be evident from the following description of the screen of the instant application.

Said screen comprises a deck or frame 10 which is rigidly attached to and vibrated by a vibratory electro-magnetic motor 11. The deck 10 is formed by a pair of spaced side walls 12, 12 which are interconnected by a plurality of transversely extending Z-shaped supporting bars 13 which are progressively so formed that the screen wire cloth 14 which is stretched across them, is arched. The side walls 12 of the deck 10 are reinforced by channel members 15 which impart rigidity to said deck, which deck is rigidly attached to a cross-head 16 formed as an integral part of an armature shaft 17 of the motor 11, the center of which armature shaft 17 is clamped to a plurality of stacked spring bars 18 the outer ends of which are rigidly clamped in a main frame casting 19.

At its upper end the armature shaft 17 carries a bracket 20 to which is attached a laminated armature 21 positioned adjacent a field structure 22 comprising a U-shaped laminated core and field windings, which field structure 22 is adjustably supported by adjusting bolts 23 in a pair of spaced U-shaped brackets 24, the lower ends of which are rigidly attached to the main frame casting 19. By energizing the field structure 22 with alternating or mixed current, the armature 21 will be attracted and released periodically, to store up energy in the spring bars 18 and release them, thus providing a straight line vibratory motion which is transferred from the motor 11 to the deck 10 through the armature shaft 17.

The screen is preferably resiliently supported by a pair of resilient spring supports 25, 25 attached to the motor 11 by brackets 26, 26 and an equalizing cross bar support 27 having hang rods attached to the two sides of the deck 10 to the center of which cross bar support a superstructure hang rod 28 is supplied.

The screen cloth 14 is rigidly attached to the deck 10 by a forward attaching cylinder 29 and adjustable attaching means 30. The manner of attaching said screen cloth is disclosed in full detail in the above mentioned patent to James A. Flint, as is the detailed structure of the vibratory motor.

Briefly described, the attaching means 30 includes a rotatable cylinder 36 extending across the deck frame 10 and received in semi-cylindrical bearings formed thereon. The cylinder has appropriate attaching rods which hook into a curved plate clamped or otherwise attached to the screen cloth 14. The outer ends of cylinder 36 have attached thereto arms 37 having their free ends bifurcated and notched to receive

trunnion nuts 38 through which thread adjusting screws 39 having adjusting heads 40 and sliding through resting bases 41 resting on brackets 42 carried by deck 10, between which heads 40 and bases 41 are springs 43. By adjusting heads 40, arms 37 may be swung to rotate cylinder 36 thereby to tension screen cloth 14.

To prevent the blinding of the screen cloth 14 whenever fine material is being screened, particularly of the type above mentioned, the screen cloth 14 is tensioned to a lesser extent than is customary with screens of this type, such for example as the screen shown in the above mentioned patent of James A Flint, to permit a reasonable amount of whipping action of said screen cloth 14. The permitting of this whipping action of the screen cloth 14 would destroy its life in a short time unless some particular means is provided to prevent such destruction. I have provided such means, which means at the same time acts as a tapper to tap the screen cloth during its vibration or whipping action to aid the whipping action of the screen in the prevention of blinding thereof.

Referring particularly to Figs. 3, 4 and 5 of the drawings, it will be seen that there is interposed between the top of each supporting bar 13 and the screen cloth, a tapper 31. Each of said tappers 31 comprises a metal plate preferably in the form of an inverted channel 32, the top of which is covered with a cap or strip 33 of resilient material, such as soft rubber. Intermediate the downwardly extending flanges of the channel 32 is a strip 34 of resilient non-metallic material which is preferably hard rubber. It is preferred that the strips 33 and 34 be rigidly attached to the channel member 32 and in practice I have done this by molding the rubber 33 and 34 directly to said channel 32, which has been found to be very satisfactory and insures a permanent bond between the channel 32 and strips 33 and 34.

Each tapper 31 is supported for vibration on a supporting bar 13 and preferably is mounted thereon as by friction attaching spring clips 35, the upper ends of which are rigidly attached to the channel 32 as by welding. It is manifest that a tapper 31 may be readily supported on a supporting bar 13 by being slipped thereover with the attaching clips in contact with said supporting bar 13. It is thus evident that the plate or channel 32 is resiliently supported upon the supporting bar 13 by virtue of the rubber strip 34, and that the screen cloth 14 is resiliently supported upon the cap or strip 33 of soft rubber. It may additionally be pointed out that the deck 10 is reinforced by a pair of longitudinally extending pipes 113 which extend through and are rigidly attached to the supporting bars 13 as by welding.

In the operation of the screen, material will be fed to the upper end and flow over the screen cloth 14, the larger particles being discharged over the lower end, and the finer particles passing through said screen cloth 14 under the vibratory action of the deck 10 which is imparted thereto by the vibratory electro-magnetic motor 11. As was previously mentioned, the screen cloth 14 is tensioned to a lesser degree than is common with screens of this general type, to permit a certain amount of whipping action thereof during vibration of the deck 10. This whipping action of the screen cloth 14 is augmented by the tapping action of the tappers 31, of which there is one on each of the supporting bars 13,

to insure against blinding of the screen cloth 14. The screen cloth in whipping is held against the soft rubber cap or strip 33 and thus will not be damaged but will effect the desired action which prevents blinding as aforementioned.

The rubber strip 34 provides a resilient non-metallic support for each tapper 31 on each supporting bar 13 and prevents a metal-to-metal contact, thereby to prevent wear on either and to reduce the noise incident to the relative motion between the channel member 32 and the supporting bar 13. During operation, the component of motion at right angles to the deck 10 tends to vibrate the tapping devices 31 relatively to the deck 10 and at right angles thereto to separate periodically the tops of cross supports 13 and the hard rubber strips 34, the soft rubber strips 33 substantially always remaining in contact with the under side of the screen cloth 14. It will thus be seen that the screen cloth may always be maintained in arched formation and stretched to exert a desired pressing down force on the rubber cushion 33 to return the tappers 31 to their initial positions relative to the supports 13 of deck frame 10. The longitudinal edges of the screen cloth 14 are free to permit a slight whipping action as a whole relatively to the deck frame 10 but it is desired to restrict this whipping action to a small amount and rely on vibrations of the tappers 31 relatively to the deck frame to secure the tapping action to jar the screen cloth 14 sufficiently to shake out therefrom the fine particles of material that tend to clog or blind the screen because of the difficulty they have in passing through the screen cloth. It should be particularly noted that the efficiency of operation of the screen is maintained by the automatic tapping action over a wide area thereof extending entirely across the latter and distributed at intervals along the latter longitudinally. Furthermore, the wear on the screen cloth where the tappers contact therewith is reduced to a minimum by the soft rubber strips 33.

It is thus evident that I have provided a relatively simple and efficient tapper to cooperate with the screen cloth which is preferably tensioned to allow a certain amount of whipping action, thereby to prevent blinding of the screen cloth whenever fine material is being screened and particularly such material as tends to blind the screen cloth, of which bauxite, alum, and silicate sand are examples.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a vibratory screen, the combination with a deck frame comprising spaced-apart side walls interconnected by a transversely extending supporting bar, of a motor connected to said deck frame to vibrate the same, a screen cloth on said frame, means for adjustably tensioning said screen cloth, and tapper means comprising a metal member having a face of resilient material in contact with said screen cloth, said metal member being mounted on said bar for automatic vertical tapper movement relatively to the latter during operation of the vibratory screen.
2. In a vibratory screen, the combination with

a frame comprising a cross-piece, of motor means connected to said frame to vibrate the same, a screen cloth, means for supporting said screen cloth on said frame to form a deck, and a tapper loosely supported on said cross-piece between said cross-piece and said screen and vibratable up and down relatively to said cross-piece, said tapper comprising a plate with cushioning material on one side in contact with said screen cloth and with hard rubber on the other side in contact with said cross-piece, the construction and arrangement being such that when said motor means operates to vibrate the said deck the said tapper will be automatically vibrated relatively to said cross-piece to prevent blinding of the screen cloth.

3. In vibratory mechanism, the combination with a frame, of a screen cloth, means for supporting said screen cloth on said frame, motor means connected to said frame to vibrate the same, a rigid member resting on said supporting means with its ends unattached thereto to enable said rigid member from end to end to vibrate freely up and down relatively to said supporting means, and a rubber buffer with its ends free from said supporting means but mounted between said rigid member and said screen cloth.

4. In vibratory screening apparatus, the combination with a frame, of a screen cloth mounted thereon to form a deck, means for vibrating said frame, a metal device mounted on said frame in fixed relation thereto except for a limited vibration relatively thereto, and a relatively narrow elongated member positioned to be compressed between said metal device and said screen cloth during operation of the screening apparatus, the contact of said elongated member with the screen cloth being maintained over a predetermined area.

5. In vibratory screening apparatus, the com-

bination with a frame comprising a cross-piece, of means for vibrating the same, a screen cloth, mechanism for supporting said screen cloth on said frame to vibrate therewith, an elongated member mounted on said cross-piece to extend along the same for vibratory movement transversely thereof, a hard rubber buffer between said elongated member and said cross-piece, and a soft rubber buffer between said elongated member and said screen cloth.

6. In vibratory screening apparatus, the combination with a frame comprising a plurality of spaced-apart cross-pieces, motor means connected to said frame to vibrate the same, a screen cloth mounted on said frame and extending over said cross-pieces to form a deck, and a plurality of tappers mounted respectively on a plurality of said cross-pieces between each of said cross-pieces and said screen cloth, each tapper having its ends free and unattached and each tapper being free to vibrate throughout its length relatively to the cross piece to which it is connected when the motor means is operated.

7. In vibratory screen apparatus, the combination with a frame comprising a plurality of cross-supports distributed longitudinally along the frame, means for vibrating said frame, a screen, mechanism for supporting said screen on said frame for vibration therewith, and a plurality of tapping devices each free and unattached at its ends and each contacting with the bottom of said screen and respectively mounted on said cross-supports each for vibration relatively thereto and each extending across substantially the entire width of said screen, the distribution of the free-ended tapping devices being over a wide area both longitudinally and laterally of the bottom of said screen.

ALEX T. CECIL.
